Primary Examiner — Ruth McInroy(74) *Attorney, Agent, or Firm* — David H. Milligan(57) **CLAIM**

The ornamental design for a garment steamer, as shown and described.

DESCRIPTION

FIG. 1 is a front and right side perspective view of a garment steamer showing our new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The details shown in broken lines form no part of the claimed design.
